UNITED STATES PATENT OFFICE.

EDWARD HOLMES AND BRITAIN HOLMES, OF BUFFALO, NEW YORK.

MACHINE FOR MAKING STAVES.

SPECIFICATION forming part of Letters Patent No. 224,187, dated February 3, 1880.

Application filed April 24, 1879.

To all whom it may concern:

Be it known that we, EDWARD HOLMES and BRITAIN HOLMES, both of the city of Buffalo, in the county of Erie and State of New York, 5 have jointly invented certain new and useful Improvements in Machines for Making Staves, which improvements are fully set forth in the following specification and accompanying drawings, in which—

10 Figure 1 is a side elevation; Fig. 2, a front elevation; Fig. 3, a vertical longitudinal section through line X X, Fig. 2; and Figs. 4 and 5 show the positions of a stave as one end reaches the inclined bed and the other end leaves the horizontal bed.

15 The object of this invention is to provide the means for hollowing out the insides of staves so as to leave the ends the required thickness; and it consists of a suitable bed, 20 cutting apparatus, and feeding device, in combination with an inclined bed for regulating the depth of the cut and its distance from the ends of the stave.

Our invention further consists in the process of hollowing out the inside of a stave by 25 feeding it over a horizontal bed, under rotary cutters, and over an inclined bed, whereby the end of the stave is lifted at the proper time to reach the cutters at the required distance 30 from the end, and continues so to rise until the necessary depth is reached, and is then carried forward in a straight line under the cutters, having its support on the extreme ends of the beds until the opposite end reaches and 35 passes along the horizontal bed, when it gradually recedes from the cutters, and then passes out of the machine, which causes that end of the stave to leave the cutters in a similar way the first end approached them, so that both 40 ends of the stave may be cut alike, as will be more clearly hereinafter shown.

In the accompanying drawings, A represents the frame of the machine; B B', the 45 driving wheel and shaft; C C' a pinion and spur-wheel, provided with a clutch, D D', for starting and stopping the machine. The shaft of the spur-wheel C' is provided with a pinion, E, which gears into the large wheel E', for moving the feeding-rollers F F'. They are 50 geared together by the wheels G G'.

H represents the bed, and H' the inclined part. The bed H is set horizontal, or at the proper angle with reference to the bed H', and both beds should be of the same length

when both ends of the stave are required to 55 be alike.

The inclined bed is arranged so that its inclination may be varied, if desired, by means of the screw-bolts I I', the operation of which is plainly shown in Fig. 2. Where staves of 60 one size only are to be hollowed out, the inclined bed could be made rigid, and the adjusting-screws could in that case be dispensed with.

J' J² represent yielding pressure-rollers for 65 holding the stave down against the beds by means of the weights K K' L L', which are connected with said rollers, as shown. A smooth bar held down by weights or springs could be used as an equivalent, or a simple 70 spring having its end pressing on the inclined bed near its upper end, so that the stave would be forced between it and the bed. In either case the pressure-rollers could be dispensed with and the same result obtained, 75 and in some cases the weight of the stave alone would answer the purpose, the object being to hold the stave toward the beds and prevent it from being drawn too far into the cutters.

80 M M' represent the cutter-heads and cutters. They are driven by a belt and pulley, N.

The upper feeding-roller is held by the arms P P' and weight R. Instead of the feeding-rollers, a pushing device, a belt, or an endless 85 chain may be used for the purpose, or the staves may be pushed into and through the machine one after the other, so that when a cheaper machine is required the feeding rollers may be dispensed with, and the beds H H' 90 may be made in one piece, if desired.

We claim as our invention—

1. In a machine for hollowing out the insides of staves, the combination, with a rotating cutter, of a horizontal bed, H, having an 95 inclined part, H', for raising the staves to the cutters, substantially in the manner and for the purposes specified.

2. The combination of a rotating cutter, the horizontal bed H, and inclined bed H', and 100 suitable devices for feeding and preventing the staves from being drawn into the cutters, substantially as specified.

EDWARD HOLMES.
BRITAIN HOLMES.
